FIG. 1 shows a front perspective view of a luggage wheel housing with a wheel;

FIG. 2 shows a right elevation view of the luggage wheel housing of FIG. 1;

FIG. 3 shows a left elevation view of the luggage wheel housing of FIG. 1;

FIG. 4 shows a front elevation view of the luggage wheel housing of FIG. 1;

FIG. 5 shows a rear elevation view of the luggage wheel housing of FIG. 1;

FIG. 6 shows a top view of the luggage wheel housing of FIG. 1; and,

FIG. 7 shows a bottom view of the luggage wheel housing of FIG. 1.

1 Claim, 7 Drawing Sheets
